UNITED STATES PATENT OFFICE

MABEL MARSH, OF MORRISTOWN, NEW JERSEY

UMBRELLA FOR CARRYING OVERSHOES

Application filed July 30, 1930. Serial No. 471,726.

This invention relates, generally, to umbrellas, and the invention has reference, more particularly to an umbrella having a novel form of handle adapted to provide a receptacle for receiving overshoes, and particularly ladies' rubber overshoes, for use during wet weather or at times when an umbrella would normally be used.

By so providing an umbrella handle with the novel overshoe container means of this invention, the user is enabled by merely carrying the umbrella to provide herself, upon the occurrence of wet weather, not only with the umbrella, but also with a pair of overshoes or rubbers.

The principal object of the present invention is to provide a novel umbrella designed for carrying overshoes, said umbrella having a handle receptacle for receiving the overshoes, said receptacle being so constructed and arranged as to provide for the easy and quick insertion of overshoes thereto as well as the removal of such overshoes therefrom.

Another object of the present invention lies in the provision of a novel umbrella of the above character having a handle provided with a removable case or cartridge adapted to contain the overshoes.

Other objects of this invention, not at this time more particularly enumerated, will be clearly understood from the following detailed description of the same.

The invention is clearly illustrated in the accompanying drawings, in which:—

Fig. 1 is a perspective view of the upper portion of the novel umbrella of the present invention and illustrates the handle in normal closed condition;

Fig. 2 is a perspective view illustrating the overshoe case removed from the handle and opened preparatory to removing the overshoes therefrom;

Fig. 3 is a sectional view taken along line 3—3 of Fig. 2; and

Fig. 4 is a vertical central view taken along line 4—4 of Fig. 1.

Similar characters of reference are employed in the above described views, to indicate corresponding parts.

Referring now to Figs. 1 to 4 of the said

drawings, the reference numeral 1 designates the novel umbrella of this invention as a whole having a hollow handle 2. Handle 2 may be made of any suitable material such as a pyroxylin derivative and is illustrated for purposes of simplicity as of cylindrical shape, although it is to be understood that the principles of this invention are applicable to handles of any exterior configuration such as tapered or many sided handles and the like. Handle 2 has a closed inner end to which the central umbrella rod 3 is secured, as by threading. The outer end of handle 2 is open for receiving an overshoe case or cartridge 4 formed preferably of sheet metal. Overshoe case 4 is of cylindrical shape and of such dimensions as to enable the same to be readily slid endwise into the hollow handle 2. The ends of case 4 are closed and access to the interior of this case is afforded by a substantially rectangular opening 5 provided in the cylindrical surface of the case. The outer end wall 6 of case 4 is preferably made of the same material as the handle 2. End wall 6 may be made in the form of a plug having a reduced portion 7 projecting into the end of case 4 and held therein as by friction, or by projections 8 formed on case 4 and extending into recesses in the portion 7. End wall 6 is preferably of the same diameter as the handle 2, so that with case 4 inserted into the handle, this end wall appears as the end of handle 2.

Case 4 is provided with opposite bayonet studs 10 on its exterior surface, which studs are adapted to engage in bayonet slots 16 formed in the inner surface of the handle 2, to thereby retain the case 4 within the interior of the handle. A rectangular closure member or cover 11 is hingedly connected to case 4 for closing opening 5. Closure member 11 is curved to conform to the wall of case 4 so that when this member closes aperture 5 its exterior surface is substantially flush with the exterior surface of the case 4. Suitable means is provided for holding cover 11 in either its closed or open positions. The means illustrated in the drawings consists of a leaf spring 12 having its ends caught and held under lugs 13 formed on case 4. The cen-

tral portion of spring 12 bears down upon the lower portion of a C member 13' which bears at its upper portion upon the outer extremity of a smaller C shaped lug 14 formed on cover 11. When cover 11 is fully open, the point of engagement of member 13' with lug 14 is positioned at one side of the line of pressure of spring 12, while when cover 11 is closed, the point of engagement of these members is at the other side of such line of pressure as will be apparent to those skilled in the art. Thus this closure means serves to cause cover 11 to push the contacts of the case inwardly thereof and retain this cover flush with the exterior surface of the case when the cover is in closed position.

In use, when it is desired to insert overshoes 15 into the umbrella handle, it is merely necessary to remove the case from the umbrella handle and, upon opening cover 11, insert the overshoes or rubbers 15 through opening 5 into this case. Case 4 is readily removed from the handle 2 by merely turning end wall 6 and hence the case about its longitudinal axis somewhat so as to thereby release studs 10 from the bayonet slots 16, whereupon the case may be drawn directly out of the interior of handle 2. Preferably the rubbers 15 are twisted together as shown in the drawings to facilitate their insertion through opening 5 but this is not essential. After the insertion of the rubbers, the cover 11 is snapped closed and held closed under the pressure of spring 12. Should any portion of the rubbers 15 tend to protrude through opening 5, the closing of cover 11 under the action of spring 12 acts to automatically push such protruding portions into the interior of case 4 so that such portions will not interfere with the easy insertion of the case into handle 2. Case 4 is now inserted into the open end of handle 2 and upon inserting studs 10 in bayonet slots 16, the end 6 is turned to thereby lock the studs in the bayonet slots. The umbrella 1 may now be carried about in the ordinary manner and upon the occurrence of wet weather, the user has both rubbers and umbrella at her command.

It will be apparent that in some instances, as for the sake of cheapness, the closure member or cover 11 may be omitted, in which case the rubbers 15 must be held inwardly of the case 4 as with the fingers while the case is being inserted into the handle.

It will be apparent that the umbrella handle 2 may be made of the same material as the case 4, such as metal in some instances, in which event the outer end wall 6 of case 4 may be made integral with the main body of this case. Also it will be apparent that the case 4 may be retained within the handle by other means than the bayonet joints illustrated, for example, a threaded connection may be used.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:—

1. In an umbrella for carrying overshoes, a hollow handle open at its outer end, an overshoe case of proportions to conform to the hollow interior of said handle and insertable through said outer end into said handle, said overshoe case having a closed inner end and being provided with an opening in the side wall thereof for receiving overshoes, and an end wall for closing the outer end of said overshoe case and the outer end of said handle.

2. In an umbrella for carrying overshoes, a hollow handle open at its outer end, an overshoe case shaped to conform to the hollow interior of said handle and insertable endwise through the open outer end of said handle into the interior thereof, said overshoe case being closed at its ends and having an opening in the side wall thereof, a closure member hingedly connected to said case for closing said opening, spring means for biasing said closure member to either closed or open positions, said case having a bayonet connection with said umbrella handle.

3. In an umbrella for carrying overshoes, a hollow handle opened at its outer end, an overshoe case of proportions to conform to the hollow interior of said handle and insertable through said outer end into said handle, said overshoe case having a closed inner end and a closed outer end and being provided with an opening in the side wall thereof for receiving overshoes, a closure member for closing said side wall opening to thereby retain overshoes therein, the closed outer end of said overshoe case serving to close the open end of the handle when said overshoe case is inserted thereinto, and fastening means on said overshoe case for removably retaining the same within said handle.

In testimony, that I claim the invention set forth above I have hereunto set my hand this 16th day of July, 1930.

MABEL MARSH.
